CLAIM

The ornamental design for an electric motor, as shown and described.

DESCRIPTION

FIG. 1 is a front side elevation view of an electric motor embodying our design;

FIG. 2 is a rear side elevation view of the electric motor.

FIG. 3 is a right side elevation view of the electric motor.

FIG. 4 is a left side elevation view of the electric motor.

FIG. 5 is a top plan view of the electric motor.

FIG. 6 is a bottom plan view of the electric motor.

FIG. 7 is a cross sectional view as taken along 7—7 line in FIG. 3, omitting the interior mechanism.

FIG. 8 is a front perspective view of the electric motor; and,

FIG. 9 is a rear perspective view of the electric motor.

The broken lines shown represent unclaimed subject matter and form no part of the claimed design.
